(57) **CLAIM**

The ornamental design for a nonwoven fabric having a surface pattern, as shown and described.

DESCRIPTION

FIG. 1 is a perspective view of a new design for a nonwoven fabric having a surface pattern;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines shown in FIGS. 1-7 illustrate portions of the nonwoven fabric having a surface pattern that form no part of the claimed design.

1 Claim, 5 Drawing Sheets
